ABSTRACT OF THE DISCLOSURE

Certain [(thenylidene amino) oxy] alkyl carboxylic acids their esters and salts have been found to have strong anti-inflammatory activities and analgetic activities.

The invention in this case relates to novel [(thenylidene amino) oxy] alkyl-carboxylic acids their salts and esters and to the use of these compounds as anti-inflammatory and analgetic agents.

Some compounds are known for the treatment of rheumatic afflictions and similar illnesses. However, these known compounds are of little value chiefly because of undesirable side effects or of a high toxicity level.

It is an object of this invention therefore to provide a new group of compounds having strong anti-inflammatory and analgetic activities while at the same time exhibiting low toxicity levels.

This and other objects of the invention will be apparent from the description that follows:

According to the invention a new and novel group of [(thenylidene amino) oxy] alkyl carboxylic acids, salts and esters thereof have been prepared. These novel compounds have the general Formula I:

wherein R₁ and R₂ are each independently hydrogen, halogen such as fluorine, chlorine, bromine or iodine or methyl, R₃ is alkylene of 1 to 3 carbon atoms inclusive for example methylene, ethylene and isopropylene, R₄ is hydrogen, alkyl of 1 to 5 carbon atoms inclusive for example methyl, ethyl, isobutyl and pentyl, alkali metal such as K and Na or the group N(H)_{4-a}(R₆)_a wherein a is an integer of 0 to 3 inclusive and R₆ is an alkyl of 1 to 5 carbon atoms inclusive or a monohydroxylalkyl of 1 to 5 carbon atoms inclusive preferably of 1 to 2 carbon atoms, examples of this group being NH₄, (C₂H₅)₂NH₂,

(C₂H₅)₃NH, (C₂H₄OH)₃NH, (C₂H₄OH), (CH₃)₂NH and (C₂H₄OH)₂(C₂H₅)NH

It has been found that these novel compounds of the invention are useful in that they generally have strong anti-inflammatory activities along with strong analgetic activities accompanied only by a very low level of toxicity.

It has been found that especially compounds of the general formula

2

wherein R₁ is bromine or chlorine and R₂ is hydrogen, bromine or chlorine have a high therapeutic index. This applies particularly to the compound [(α-methyl-5-chloro-2-thenylidenediamino) oxy] acetic acid and its salts.

Because of their pharmaceutical properties the compounds of the invention are useful in treating such diseases of mammals as rheumatoid arthritis, Bechterew's disease, arthritis psoriacta, collagen diseases, osteoarthritis, acute lumbago, humeroscapular periarthritis, acute sterile non-infected bursitis, thrombophlebitis and acute rheumatic polyarthritis.

The dosage which, and the frequencies at which, the compounds are to be administered for treating these afflictions depends on the seriousness thereof. As a rule, the physician treating the patient will have no difficulty in arriving at the right treatment. Generally, from 50 to 1000 mg. daily will be administered to the patient, which may be divided into several portions. As a rule, 100 to 500 mg. daily will be sufficient. The compounds may be administered orally, parenterally or rectally.

The anti-inflammatory effect of the compounds was determined by the carragheenin test carried out according to a modification of the method of Winter, Risley and Nuss, Proc. Soc. Exp. Biol. 111—544 (1962).

In this test the reduction of the edema produced by carragheenin serves as a measure of the anti-inflammatory activity.

The test was made with male rats, weight about 220 g. The animals were made to fast for the 16 hours preceding the test. The substance to be tested is suspended in 1% tragacanth solution and administered orally. The administration of the substance is immediately followed by water loading up to 5 ml. per animal. 1 hour after the administration of the test substance and the water loading 0.05 ml. of a 1½% carragheenin solution is injected intraplantarly and the thickness of the legs (dorsal plantar distance) is determined by means of a specially constructed micrometer.

3 hours after the administration of the carragheenin the thickness of the edema produced is determined. The swelling of the leg is expressed as a percentage relative to the zero-hour value. The percentage of the inhibition is calculated according to the relation:

$$\frac{\text{percent blank} - \text{percent test group}}{\text{percent blank} - 100}$$

From the results of a series of dosages an ED₅₀ value was computed. This is the amount which causes a reduction of 50% relative to the blank percent group.

The analgetic activity of the compounds was determined according to a modification of the method of Randall and Sellito (Arch. Int. Pharmacodyn. 109—409 (1957)).

The decrease of the response to pain due to increasing pressure of a rat's leg inflamed by means of yeast serves as a criterion for the analgetic effect.

The test is performed on male rats having weights between 100 and 150 g. One hour before the administration of the test preparation the animals are intraplantarly

injected with 0.1 ml. of a 20% yeast suspension. The compounds to be tested are suspended in a 1% tragacanth solution and administered orally. One hour, two hours and four hours after the administration of the test substance, the pain threshold is measured with increasing pressure on the inflamed leg.

As a control the pain reactions of a group of animals which have not been treated with the pharmacon are determined.

These results are expressed as a percentage of the mean blank value.

From the results of a series of dosages an ED_{50} value was computed, i.e. the dosage which produces a 100% rise of the pain threshold.

The compounds of the invention may be prepared according to methods analogous to those known in the art for preparing similar compounds.

The compounds according to the invention are obtainable, for example, by reacting a compound of the Formula II

which can be produced from the corresponding ketone by means of hydroxyl amine, with a compound of the Formula III

in which formulae R_1 to R_3 have the same meanings as in the Formula I, M is a metal atom, for example Na or K, Hal is a halogen atom, for example chlorine or bromine and R_4' is hydrogen, an alkyl containing up to 5 carbon atoms or an alkali metal, and, if desired, by converting the resulting acids into salts. The reaction is preferably performed in a polar solvent such as dimethyl formamide, dimethyl sulphoxide, alcohols and the like, at temperatures between room temperature and the boiling temperature of the reaction mixture and in the presence of an acid binder, such, for example, as an ethanolate.

The compounds according to the invention may alternatively be prepared by reacting a compound of the general Formula IV

with a compound of the general Formula V

in which formulas the symbols have the same meanings as in the Formula I. This reaction also is preferably carried out in a polar inert solvent, for example one of the aforementioned solvents. As a rule, the reaction temperature will lie between room temperature and the boiling point of the solvent.

The compounds of the Formula VI

in which formula R_1 , R_2 and R_4 have the same meanings as in the Formula I and R_3' represents a propylene or a possibly branched methylene group, can be prepared by

reacting a compound of the Formula II with a compound of the Formula VII:

after which the resulting acids may be esterified or converted into their salts.

The reaction is preferably performed in an inert solvent such, for example, as N-methyl-2-pyrrolidone, benzene and the like, at temperatures between room temperature and the boiling point of the solvent.

The compounds of the Formula VI may alternatively be produced by reacting a compound of the Formula II with a compound of the Formula VIII,

where R_3'' is an ethylene group of a propenyl 1, -2 or -3 group. The reaction is preferably performed in an inert solvent, for example in an alcohol, for example ethanol. The reaction temperature as a rule lies between 0° C. and the boiling point of the reaction mixture.

The compounds of the Formula I may also be obtained by saponifying a nitrile of the Formula IX

where R_1 to R_3 have the same meanings as in the Formula I, with an alkaline solution and, if desired, by converting the resulting salt into other salts, into the free acid or into an ester. The reaction is preferably carried out in an inert solvent, such as an alcohol, at a temperature below the boiling point of the reaction mixture.

The nitriles of the Formula IX are obtainable by converting a halogen alkyl nitrile with a compound of the Formula II in a polar solvent.

Esters of the Formula X,

where R_4'' represents an alkyl group containing up to 5 carbon atoms and R_1 to R_3 have the same meanings as in the Formula I, may alternatively be obtained by reacting a nitrile of the Formula IX with an alcohol $R_4''\text{OH}$ in the presence of an acid and by subsequently decomposing the reaction product with water. The reaction is preferably carried out in an inert solvent, for example an ether, such as diisopropyl ether. The reaction temperature lies between 0° C. and 40° C. Acids of the Formula I may be converted into the corresponding esters of the Formula I with alcohols, if required via the acid chlorides. From esters of the Formula I the acids of the Formula I are obtainable by saponification.

The compound according to the invention may be made up into pharmaceutical preparations such as, for example, tablets, pills, powders, injection liquids, salves, suppositories, dragees and the like, by known methods. Hence, the invention also relates to the production of pharmaceutical preparations and to the preparations themselves.

As carrier materials the substances commonly used in pharmaceutics may be employed.

Examples of such carrier materials are water, corn starch, gelatine, lactulose, sucrose, talc, vegetable gums, propylene glycol, polyalkylene glycols, white petroleum jelly and other known pharmaceutical carriers.

The pharmaceutical composition of the invention is useful in treating many mammals including dogs, horses as well as humans.

The invention will now be described more fully with reference to the following examples:

(1) $[(\alpha\text{-methyl-4-bromo-2-phenylidene amino})\text{oxy}]$ acetic acid.—A solution of 4.2 g. of 4-bromo-2-acetylthiophene in 42 ml. of ethanol was mixed with 2.2 g. of hemihydrochloride of 2-amino oxyacetic acid and then with a hot solution of 4.90 g. anhydrous sodium acetate in 8 ml. of water. The reaction mixture was then boiled under a reflux condenser for 3 hours. After a small amount of solvent had been distilled off in a vacuum, the sodium salt of the reaction product crystallized out. This was filtered off and the filtrate was evaporated further in a vacuum. The solid substance filtered off was dissolved, together with the obtained residue, in 100 ml. of water, 20 ml. of 2 N solution of caustic soda and 30 ml. of ether. The ethereal layer was separated off and the alkaline layer was extracted 2 times with 40 ml. of ether. The alkaline water layer was then acidified with 10 ml. of concentrated hydrochloric acid and again extracted 3 times with ether. The latter ethereal extract was dried over anhydrous sodium sulfate, and subsequently the solvent was removed. The resulting $[(\alpha\text{-methyl-4-bromo-2-phenylidene amino})\text{oxy}]$ acetic acid was crystallized from a small amount of benzene (2 g. from 10 ml.) and melted at 140–141° C.

(2) $[(\alpha\text{-methyl-5-chloro-2-phenylidene amino})\text{oxy}]$ acetic acid.—A solution of 5.4 g. of 5-chloro-2-acetyl thiophene in 100 ml. of 80% ethanol was mixed with 4.4 g. of hemihydrochloride of aminooxyacetic acid and 9.8 g. anhydrous sodium acetate, and the mixture was boiled under a reflux condenser for 1 hour. The reaction was then evaporated to dryness in a vacuum, the residue being mixed with 75 ml. of 2 N solution of caustic soda. The mixture was washed 2 times with ether. The alkaline water layer was then acidified with 125 ml. of 2 N hydrochloric acid and then extracted 3 times with ether. The latter ethereal extract was washed 3 times with small amounts of water and then dried over anhydrous sodium sulfate. The solvent was removed from the dried solution by evaporation, and the residue was crystallized with a mixture of benzene and petroleum ether. Thus, the $[(\alpha\text{-methyl-5-chloro-2-phenylidene amino})\text{oxy}]$ acetic acid crystallized out which had a melting range from 116° C. to 132° C.

In a manner corresponding to those described in Examples 1 and 2 there were produced:

(3) $[(\alpha\text{-methyl-2-phenylidene amino})\text{oxy}]$ acetic acid, melting range 91° C.–118° C.

(4) $[(\alpha\text{-methyl-3,4-dibromo-2-phenylidene amino})\text{oxy}]$ acetic acid, melting point 166–168° C.

(5) $[(\alpha\text{-methyl-2,5-dichloro-3-phenylidene amino})\text{oxy}]$ acetic acid, melting point 97° C.–98° C.

(6) $[(\alpha,5\text{-dimethyl-2-phenylidene amino})\text{oxy}]$ acetic acid.

To a solution of 1.85 g. of sodium in 150 ml. of ethanol there were successively added, with stirring, 6.2 g. of 5-methyl-2-acetyl-thiophene oxime and 7.8 g. of bromoacetic acid. The mixture was stirred for 1 hour, after which the ethanol was removed in a vacuum. The resulting residue was mixed with water, the mixture being extracted 3 times with ether. The aqueous alkaline solution was acidified with 2 N hydrochloric acid and again extracted 3 times with ether. The latter ethereal extract was washed 4 times with water and then dried over anhydrous sodium sulfate. After the solvent had been distilled off, the residue was crystallized from a mixture of benzene and petroleum ether. The resulting $[(\alpha,5\text{-dimethyl-2-phenylidene amino})\text{oxy}]$ acetic acid melted at 126–127° C.

(7) $4-[(\alpha\text{-methyl-5-chloro-2-phenylidene amino})\text{oxy}]$ butyric acid.—2.0 g. of 5-chloro-2-acetylthiophene oxime was added to a solution of 0.26 g. of sodium in 15 ml. of absolute ethanol. After the oxime had dissolved, the solvent was distilled off in a vacuum and the residue was dissolved with heating in 10 ml. of N-methylpyrrolidone-2. To this solution there was added 0.87 ml. of butyric

olactone. The mixture was boiled under a reflux condenser for 4 hours. The hot reaction mixture was then poured in water and the aqueous solution was filtered. The filtrate was acidified with acetic acid and the solid precipitate was drawn off. This solid substance was dissolved in acetone, the aceton solution was treated with activated carbon and, after filtration, evaporated to dryness. The residue was crystallized from 30% acetic acid, the $4-[(\alpha\text{-methyl-5-chloro-2-phenylidene amino})\text{oxy}]$ butyric acid being obtained, melting point 92° C.–96° C.

(8) $2-[(\alpha\text{-methyl-5-chloro-2-phenylidene amino})\text{oxy}]$ acetic acid methyl ester.—A solution of 1.0 g. of $2-[(\alpha\text{-methyl-5-chloro-2-phenylidene amino})\text{oxy}]$ acetic acid in 10 ml. of methanol was mixed with 3 drops of concentrated sulfuric acid and then boiled under a reflux condenser for 18 hours. The methanol was then distilled off in a vacuum and the residue was dissolved in 25 ml. of ether. The ethereal solution was washed successively with water (3 times with 10 ml.), with 10 ml. of 2 N sodium hydroxide and again 3 times with 10 ml. of water. The solution was then dried over anhydrous sodium sulfate and, after filtration, evaporated in a vacuum. The residue, $2-[(\alpha\text{-methyl-5-chloro-2-phenylidene amino})\text{oxy}]$ acetic acid methyl ester, was crystallized from 47 ml. of petroleum ether, boiling range 40° C.–60° C. Melting point 99–101° C.

(9) Tablet containing 0.2 g. of $[(\alpha\text{-methyl-5-chloro-2-phenylidene amino})\text{oxy}]$ acetic acid.—200 g. of $[(\alpha\text{-methyl-5-chloro-2-phenylidene amino})\text{oxy}]$ acetic acid was mixed with 190 g. of sec. calcium phosphate, 90 g. of microcrystalline cellulose and 120 g. of a mixture consisting of 200 parts of maize starch, 32 parts of talcum and 4 parts of magnesium stearate, until the mixture was homogeneous. From this mixture tablets having a diameter of 13 mm. and a weight of 600 mg. were struck.

(10) Suppository containing 0.1 g. of $[(\alpha\text{-methyl-5-chloro-2-phenylidene amino})\text{oxy}]$ acetic acid.—100 mg. of $[(\alpha\text{-methyl-5-chloro-2-phenylidene amino})\text{oxy}]$ acetic acid was formulated with 1.5 g. of suppository material into a suppository.

(11) Injection liquid.—100 mg. of $[(\alpha\text{-methyl-5-chloro-2-phenylidene amino})\text{oxy}]$ acetic acid was dissolved in an equimolar amount of 1 N sodium hydroxide, and the solution was mixed with 15 g. of benzyl alcohol. This solution was then diluted to a volume of 1000 ml. with distilled water. It was then strained through a bacterial filter, after which ampoules of 1 or 2 ml. were aseptically filled with the liquid.

What we claim is:

1. A compound of the formula:

wherein R_1 is a moiety selected from the group consisting of chlorine and bromine, R_2 is a moiety selected from the group consisting of hydrogen, chlorine and bromine, R_3 is methylene and R_4 is a moiety selected from the group consisting of hydrogen, alkyl of 1 to 5 carbon atoms inclusive, alkali metal and an ammonium group of the formula $\text{N}(\text{H})_{4-a}$ (R_6) $_a$ wherein a is an integer of 0 to 3 inclusive and R_6 is a moiety selected from the group consisting of alkyl of 1 to 5 carbon atoms inclusive and monohydroxyalkyl of 1 to 5 carbon atoms inclusive.

2. As a compound of claim 1, $2-[(\alpha\text{-methyl-5-chloro-2-phenylidene amino})\text{oxy}]$ acetic acid methyl ester.

3. As a compound of claim 1, a 2-phenylidene derivative selected from the group consisting of $[\alpha\text{-methyl-5-bromo-2-phenylidene amino})\text{oxy}]$ acetic acid and its alkali metal salts.

4. As a compound of claim 1, a 2-thenylidene derivative selected from the group consisting of [α -methyl-5-chloro-2-thenylidene amino)oxy]acetic acid and its alkali metal salts.

5. As a compound of claim 1, a 2-thenylidene derivative selected from the group consisting of [α -methyl-3,4-dibromo-2-thenylidene amino)oxy] acetic acid and its alkali metal salts.

6. As a compound of claim 3, a 2-thenylidene derivative selected from the group consisting of [α -methyl-2,5-dichloro-3-thenylidene amino)oxy] acetic acid and its alkali metal salts.

7. As a compound of claim 1, a 2-thenylidene derivative selected from the group consisting of [α -methyl-5-

chloro-2-thenylidene amino)oxy] acetic acid and its alkali metal salts.
